UNITED STATES PATENT OFFICE.

CECIL J. LANCASTER, OF RICHMOND, VIRGINIA.

SAFETY-SHUTTER.

1,267,087.

Specification of Letters Patent. Patented May 21, 1918.

Application filed August 24, 1917. Serial No. 187,990.

To all whom it may concern:

Be it known that I, CECIL J. LANCASTER, a citizen of the United States, residing at Richmond, in the county of Henrico, State of Virginia, have invented a new and useful Safety-Shutter; and I do hereby declare the following to be a full, clear, and exact description of the invention, such as will enable others skilled in the art to which it appertains to make and use the same.

10 This invention relates to an improved safety shutter.

An object of the invention is to provide an improved shutter, which is simple, practical and efficient in construction, and constructed entirely of sheet metal, consequently providing a strong and durable and fire-proof shutter designed for use on houses, apartments, factories and various other buildings, where shutters are necessary, hence producing a more efficient burglar-proof shutter.

20 A further object of the invention is to provide a metallic shutter consisting of a frame of a general outline similar to the old style wood shutter, and in which sheet metal slats are mounted, whereby they may be adjusted in various ways.

25 A further object of the invention is to provide a shutter having an upper plurality of slats and a lower plurality of slats, the upper plurality being collapsible upwardly, and the lower plurality collapsible downwardly, in combination with means whereby

30 each plurality may be collapsed.

35 A further object of the invention is the provision of link connections between the slats, whereby the slats may be easily collapsed, said link connections being so arranged and constructed as to prevent binding, during their collapsing actions.

40 A further object of the invention is the provision of means for holding the slats of the shutter in uniform parallelism, and means to maintain such parallelism, when raising or lowering the slats.

45 A further object of the invention is the provision of raisable and lowerable slats, whereby a thorough ventilation may be obtained without opening the shutter frame.

50 A further object of the invention is the provision of means for locking the adjacent end slats of the upper and lower pluralities together, when the upper plurality is lowered and the lower plurality raised.

55 A further object of the invention is the

provision of means carrying said locking means, and also having such connections with said slats, whereby they may be tilted on different angles, the slats of each plurality regardless of their angles being uniform in parallelism.

In practical fields, the details of construction may necessitate alterations, falling within the scope of what is claimed.

60 The invention comprises further features and combination of parts, as hereinafter set forth, shown in the drawings and claimed.

In the drawings:—

Figure 1 is a view in side elevation of an improved shutter constructed in accordance with the invention and applied to a window frame.

Fig. 2 is a vertical sectional view on line 2—2 of Fig. 1, showing the upper and lower pluralities of slats brought together.

Fig. 3 is an edge view of the improved shutter, also showing the upper and lower pluralities of slats brought together.

Fig. 4 is an edge view of the shutter, showing the upper and lower pluralities of slats raised and lowered, consequently entirely collapsed together.

Fig. 5 is a sectional view on line 5—5 of Fig. 4.

Fig. 6 is a transverse sectional view on line 6—6 of Fig. 4.

Fig. 7 is a vertical sectional view on line 7—7 of Fig. 4, showing the slats of the shutter in edge elevation, and also illustrating the link connections between the slats.

Fig. 8 is an edge view of the lower part of the shutter, and illustrating a portion of the window frame in section, and also showing the means for tilting the slats of the lower plurality on different angles.

Fig. 9 is an enlarged detail perspective view of a portion of the upper plurality of slats, showing their link connections, and a portion of the means for manipulating the slats.

Fig. 10 is an edge view of the upper part of the shutter, and a portion of the window frame in section, and showing the means for tilting the slats of the upper plurality on different angles.

Fig. 11 is an enlarged detail view of several slats of the lower plurality, showing them in their collapsed condition.

Referring more especially to the drawings, 1 designates a conventional form of window frame, which in Fig. 1 of the draw-

ing is shown in elevation, and as viewing the same from the interior of a room, and 2 denotes the improved shutter frame, a part of which is shown in dotted lines in Fig. 1. 5 This shutter frame in general outline resembles the shape of the usual wood shutter frame, and as shown in Figs. 2 and 6, the upper end and side rails are U-shaped in cross section. The side rails 3 of the shutter 10 frame are provided with guide slots 4, and 5 and 6 denote the plurality of slats of the upper and lower sets. Each slat of either set is constructed of sheet metal, and adjacent each end of each slat transverse slots 7 15 and 8 are constructed. The inner ends of the slots 7 and 8 almost join, in which case there is a small neck 9 formed. The necks 9 engage the guide slots 4, while the slots 7 and 8 engage the flanges 10 of the shutter 20 frame, and by this arrangement and construction the slats are guided in their raising and lowering movements. On each slat between the slots 7 and 8 and each extreme end of the slat, a U-shaped cutaway portion 25 is constructed. The cutaway portion 11 at each end of every other slat has a lug 12 projecting from its crotch. The ends of the slats of each set are connected by links 13 and 14 arranged in pairs, each pair in staggered relation with an adjacent pair. These 30 links are pivoted at 15 and 16 to the end edges of the slats, near the corners thereof, and the links of each pair are pivotally united as shown at 17. The link 14 of each 35 pair has one of its edges, near its pivot 17 provided with a laterally extending lug 18, which overlies the inner edge of the link 13, as shown clearly in Figs. 3, 8, 9, and 10. Each lug 18 is so constructed and so arranged 40 overlying the link 13, as to prevent the links of each pair from entirely straightening out. In fact, by means of the lug 18, when the slats are separated as shown in Fig. 9, the links 13 and 14 are held at a slight 45 obtuse angle to each other, as clearly shown in Fig. 10, so that when it is desired to raise the slats or collapse them, said slats will move or collapse toward each other without binding, in other words the links will pivot 50 without buckling. The marginal edge 19 of the cutaway portion 11 (which is without the lug 12) of every other slat of each set has pivoted thereto as shown at 20 a link 21, which in turn is pivoted at 22 to a link 23. 55 The link 23 is in turn pivoted at 24 to one edge of the lug 12 of the cutaway portion 11 of every other slat. Pivoted at 25 to the opposite edge of said lug 12 is a link 26, which in turn is pivoted at 27 to a link 28, 60 which in turn is pivoted at 29 to the edge 30 opposite the edge 19 of the cutaway portion 11 of every other slat. This arrangement of links 21, 23, 26 and 28 is carried out, whereby the slats of both sets are additionally connected sequentially, and to main-

tain them in uniform parallelism, whether they are opened, separated or disposed at angles. Each link 21 and each link 26, adjacent where it is pivoted to its adjacent link is provided with a lateral lug 31, to overlie its adjacent link, and to prevent such joined links from straightening out entirely. In other words, by means of the lugs 31 said links 21 and 23, or 26 and 28, are held at a very slight obtuse angle, as shown in Figs. 70 8 and 10, whereby, when it is desired to bring the slats together or collapse them, the links will pivot without buckling. The lower slat of the upper plurality at both ends, and the upper slat of the lower plurality at both ends are provided with projections 32 and 33. Connected to an eye of one of the projections 32 at one end of the lower slat of the upper plurality is a cable or the like 34, which passes over a pulley 85 35 in the upper part of the shutter frame and has its end terminating in a handle 36 located on the inner side of the window frame substantially midway of its height, whereby said cable or the like may be pulled. A 90 cable 37 is connected to an eye of the opposite projection 32 and extends upwardly through the side rail of the shutter frame and over a pulley 38, and thence over a pulley 39 near but on an axis at right angles to 95 the axis of the pulley 35, and is then extended through the window frame on the interior of the room terminating in a handle 40 suspended substantially midway of the height of the window frame. Thus it will 100 be seen that by pulling upon said cables 34 and 37 the slats of the upper plurality may be collapsed upwardly, as shown in Fig. 4 clearly. Connected to the opposite projections 33 are cables 41 and 42. The cable 41 105 passes upwardly to one of the side rails of the shutter frame and over a pulley 43, and passes through the upper part of the shutter frame to the interior of the room and terminates in a handle 44 located substantially 110 midway of the height of the window frame. The cable 42 or the like extends upwardly through the other side rail of the shutter frame and passes over a pulley 45 and through the top rail of the shutter frame 115 and thence over the pulley 46, and then through the shutter frame to the interior of the room and terminates in a handle 47, which is also arranged substantially midway of the height of the window frame. It is to 120 be noted that the lower plurality of slats may collapse downwardly by gravitation. However, to raise the lower plurality of slats, it is required that a pulling action be imparted on the cables 41 and 42. The side 125 rails of the shutter frame midway their heights have mounted in bearings thereof shafts 48 and 49. These shafts are designed to have slight axial movements, the purpose of which will appear later. Mounted upon 130

the shaft 48 and keyed thereto by the pins 50 are pulleys 51 and 52, and mounted upon the shaft 48 and between the said pulleys is a sleeve 53, in which said shaft 48 is allowed 5 to slightly rock. A spring 54 is interposed between the pulley 52 and one wall of the shutter frame, so as to hold the other pulley 51 adjacent the opposite wall of the shutter frame. The inner end of the shaft 48 10 has a rectangular portion 55. By applying any suitable means (such as will be described later) to the rectangular end 55 the shaft 48 may be rocked. A suitable cable or cord 56 is connected to and wound partially about 15 the pulley 51 in one direction, and has its upper end connected to one corner of one end of the uppermost slat of the upper plurality. Another cable or cord 57 is connected to and wound about the other pulley 52 in the opposite direction, and has its upper 20 end connected to the opposite corner of the same end to which the cable 56 is connected of the uppermost slat of the upper plurality. Hence, when the shaft 48 is rocked in one 25 direction or the other, it will be noted that since the slats are joined sequentially, they may be tilted on their pivots, to assume uniform inclinations. The shaft 49 is provided with pulleys 59 and 60. These pulleys are 30 fast on the shaft, and have cables or cords 61 and 62 connected thereto and wound thereabout in opposite directions, and their lower ends are connected at 63 to the adjacent corners of one end of the lower slat of 35 the lower plurality of slats, so that by turning the shaft 49 in one direction or the other the slats 6 may be tilted at uniform inclinations. A sleeve 64 is also loose upon the shaft 49 between the pulleys 59 and 60, and 40 there is a spring 65 interposed between the pulley 59 and one wall of the shutter frame, serving to hold the other pulley 60 normally adjacent the opposite wall of the shutter frame. Said sleeves 53 and 64 have radial 45 arms 66 and 67, which are provided with hooks 68 and 69. These hooks are designed to engage the projections 32 and 33 of the meeting slats of the upper and lower plurality of slats, that is, when the upper 50 plurality of slats is lowered and the lower plurality of slats is raised, thereby holding said slats in such lowered and raised positions. In order to rock or move each shaft 48 and 49, the window frame where each shaft projects 55 toward the frame is provided with an opening 70. Mounted in the opening 70 is a shaft 71 having a head 72 provided with a rectangular socket 73, to engage the rectangular end 55 of either shaft, so that by 60 turning the shaft 71 one or the other of the shafts 48 and 49 may be rocked. The shaft 71 is mounted in a bearing plate 73^a which is secured by screws 74 to the window frame, and interposed between the bearing plate 65 and the head 72 is a coil spring 75. This shaft 71 has a crank 76 and handle 77. It will be seen that by turning the crank the shaft 71 is rotated, and in turn the shaft 48 may be rotated in one direction or the other, and through the medium of the cables 56 and 70 75 57 the slats may be tilted. It may also be observed that when the shaft 71 is moved axially toward the shaft 48, said shaft 48 will also be moved axially, which will release the hooks 68 from the projections 32 75 and 33. The same functions may be performed by the shaft 49, by correspondingly operating the other shaft 71 and its crank. The lower end of the shutter frame is provided with an extension 80, which is U- 80 shaped, and fits the shutter frame. As shown in Figs. 2 and 3, the sides of the U-shaped extension are provided with slots 81, for the reception of the screws 82, and it is to be noted that by loosening and tightening 85 said screws 82, said U-shaped extension may be adjusted and secured in its adjusted position.

The invention having been set forth, what is claimed as new and useful is:—

1. In a shutter, a shutter frame, upper and lower pluralities of slats mounted in guides of said frame and having link connections whereby said slats may be tilted on uniform angles and collapsed upwardly and 95 downwardly, means for bringing together and separating said upper and lower pluralities of slats, a sliding member, the meeting slats of the upper and lower pluralities having projections, said sliding member having hooks to engage said projections for locking the upper and lower pluralities 100 of slats together.
2. In a shutter, a shutter frame, upper pluralities of slats mounted in guides of said frame and having link connections whereby said slats may be tilted on uniform angles and collapsed upwardly and downwardly, means for bringing together and separating said upper and lower pluralities of slats, a 110 sliding member, the meeting slats of the upper and lower pluralities having projections, said sliding member having hooks to engage said projections for locking the upper and lower pluralities of slats together, said sliding member adapted to be rotated and having means connected to said slats for tilting them on uniform angles.
3. In a safety shutter, a shutter frame, upper and lower pluralities of slats slidably 120 mounted in guides of said frame, said slats having connecting means whereby they are joined sequentially and in parallelism, means for bringing together and separating the upper and lower pluralities of slats, the meeting slats of the upper and lower pluralities having devices, a pair of slidable and rockable elements, having members to engage said devices for locking the upper 125 and lower pluralities of slats together, and 130

- means connecting said elements and the slats, whereby, as said elements are rocked, said slats may be tilted upon uniform angles.
5. 4. In a safety shutter, a shutter frame, upper and lower pluralities of slats mounted in guides of said frame, means for pivotally uniting said slats sequentially, the meeting slats of the upper and lower pluralities of 70 slats having projections, axially slid able and rockable elements having devices to engage said projections for locking the upper and lower pluralities of slats together, means connecting said elements and the upper and 10 lower pluralities of slats, whereby, as said element is rocked in one direction or the other, said slats may be tilted on uniform angles.
15. 5. In a safety shutter, a shutter frame, upper and lower pluralities of slats mounted in guides of said frame, means for pivotally uniting said slats sequentially, the meeting slats of the upper and lower pluralities of slats having projections, axially 80 slid able and rockable elements having devices to engage said projections for locking the upper and lower pluralities of slats together, means connecting said elements and the upper and lower pluralities of slats, 85 whereby, as said element is rocked in one direction or the other, said slats may be tilted on uniform angles, and means for operating said elements either axially or rockably.
20. 6. In a safety shutter, a shutter frame, a plurality of parallel pivotally united slats mounted in guides of said frame, a rockable element, and means wound about said element in opposite directions and connected thereto, and in turn connected to said slats, 90 whereby as said element is rocked, said slats may be tilted on uniform angles, and means carried by said element to engage adjacent slats for locking the same together.
25. 7. In a safety shutter, a shutter frame, a plurality of parallel pivotally united slats mounted in guides of said frame, a rockable element, and means wound about said element in opposite directions and connected thereto, and in turn connected to said slats, 95 whereby as said element is rocked, said slats may be tilted on uniform angles, means carried by said element to engage adjacent slats for locking the same together, and means for rocking said element, and for 100 sliding said element, whereby said locking means may be disengaged from said adjacent slats.
30. 8. In a safety shutter, a shutter frame, a plurality of parallel pivotally united slats 105 slidably mounted in guides of said frame, means for collapsing said slats upwardly, and whereby said slats may lower by gravitation when said means is released, an axially slid able and rockable element mounted 110 in bearings of said frame, the lowermost 115 slat having projections, a sleeve axially movable with said element and in which said element is rockable, said sleeve having hooks to engage said projections to lock the slats in their lowered positions, and means for sliding said element to engage or disengage said hooks to and from the projections.
35. 9. In a safety shutter, a shutter frame, a plurality of parallel pivotally united slats 120 slidably mounted in guides of said frame, means for collapsing said slats upwardly, and whereby said slats may lower by gravitation when said means is released, an axially slid able and rockable element mounted in bearings of said frame, the lowermost 125 slat having projections, a sleeve axially movable with said element and in which said element is rockable, said sleeve having hooks to engage said projections to lock the slats in their lowered positions, means wound about said element in opposite directions and connected thereto, and in turn connected to said slats, whereby, as said element is rocked in one direction or the other, said slats may be tilted on uniform angles, and means for operating said hooks or said last named means.
40. 10. In a safety shutter, a shutter frame having guides, a plurality of parallel slats mounted in said guides, means for collapsing 130 said slats upwardly, a plurality of pairs of links, said pairs of links being arranged in staggered relations and connecting the opposite corners at one end of said slats, each pair of links connecting the corresponding ends of two adjacent slats being in staggered relations to those links connecting corresponding ends at the opposite ends of the same slats.
45. 11. In a safety shutter, a shutter frame having guides, a plurality of parallel slats mounted in said guides, means for collapsing 135 said slats upwardly, a plurality of pairs of links, said pairs of links being arranged in staggered relations and connecting the opposite corners at one end of said slats, each pair of links connecting the corresponding ends of two adjacent slats being in staggered relations to those links connecting corresponding ends at the opposite ends of the same slats, the end portions of said slats having cutaway portions, the cutaway portions of every other slat having lugs projecting from their crotches, and links arranged in pairs and pivotally united and connecting the lugs with the marginal opposite edges of the cutaway portions of every other slat without said lugs, said links having means at their pivotal unions to hold the links at very slight obtuse angles, whereby they may pivot without binding when collapsing the slats.
50. 12. In a safety shutter, a shutter frame having guides, a plurality of parallel slats 140 mounted in said guides, means arranged in 145

staggered relations connecting the corresponding corners at every other end of each two adjacent slats, the end portions of said slats having cutaway portions, the cutaway 5 portions of every other slat having lugs projecting from their crotches, links arranged in pairs and pivotally united and connecting the lugs with the marginal opposite edges of the cutaway portions of every other 10 slat without said lugs, and means adjacent the pivotal connections of the links to hold the links at slight obtuse angles, whereby they may pivot without binding when collapsing the slats, and means for collapsing 15 the slats.

13. In a safety shutter, a shutter frame having guides, a plurality of parallel slats mounted in said guides, means for collapsing said slats upwardly, a plurality of pairs 20 of links, said pairs of links being arranged in staggered relations and connecting the opposite corners at one end of said slats, each pair of links connecting the corresponding ends of two adjacent slats being 25 in staggered relations to those links connecting corresponding ends at the opposite ends of the same slats, the end portions of said slats having cutaway parts, means sequentially connecting the crotches of every other 30 slat with the marginal opposite edges of the cutaway parts of the intermediate slats, said means having devices for preventing the means from binding when collapsing the slats.

14. In a safety shutter, a shutter frame, a 35 plurality of parallel pivotally united slats, said frame having guides for said slats, said slats comprising upper and lower series, means for collapsing the upper series 40 upwardly, means for collapsing the lower series downwardly, an axially slideable and rockable member intermediate the upper and lower series, means surrounding the member and connected thereto, and in turn 45 connected to the slats of one of the series for tilting the slats on uniform angles, and a sleeve movable axially with the member and having devices to engage the adjacent slats of the upper and lower series to hold 50 the same drawn together.

15. In a safety shutter, a frame, upper and lower series of parallel coupled slats in guides of said frame, means for drawing the two series together at a point between the ends of the frame, and a reciprocating 55 device having means engaging the adjacent end slats to lock them together.

16. In a safety shutter, a frame, upper and lower series of coupled slats in guides of said frame, means for drawing the two 60 series together at a point between the ends of the frame, a movable device having elements engaging the adjacent end slats of the series to lock them together, said device being revolvable and having means wound 65 thereabout and connected to the slats for tilting them on different angles.

17. In a safety shutter, a frame, upper and lower series of coupled shutter slats in guides of said frame, a reciprocating and 70 revolvable device having elements, adapted when the device is reciprocated, to engage the adjacent end slats of the series to lock them together.

18. In a safety shutter, a frame, upper 75 and lower series of coupled shutter slats in guides of said frame, a reciprocating and revolvable device having elements, adapted when the device is reciprocated, to engage the adjacent end slats of the series to lock 80 them together, and means wound around said device and connected to the slats, whereby as the device is rotated the slats may be tilted.

19. In a safety shutter, a frame, upper 85 and lower series of coupled slats in guides of said frame, a device movable in one direction and having hooked arms engaging the adjacent end slats of the series to lock them together, said device being movable 90 at right angles to its first movement and having means connected thereto and to the slats for tilting them on different angles.

In testimony whereof I have signed my name to this specification in the presence of 95 two subscribing witnesses.

CECIL J. LANCASTER.
